UNITED STATES PATENT OFFICE.

WILLIAM H. MULLINS, OF SALEM, OHIO.

DESIGN FOR A ROOFING-TILE.

SPECIFICATION forming part of **Design No. 24,084, dated March 5, 1895.**

Application filed September 26, 1894. Serial No. 524,207. Term of patent 7 years.

To all whom it may concern:

Be it known that I, WILLIAM H. MULLINS, a citizen of the United States, residing at Salem, in the county of Columbiana and State of Ohio, have invented and produced a new and original Design for a Roofing-Tile, of which the following is a description, reference being had to the accompanying drawing, in which the figure is a perspective view illustrating my design.

The general purpose of this design is the adornment of roofs for buildings, having as a primary object the production of a roofing-tile which is attractive to the eye and suitable for use wherever slate, tiles, or shingles could ordinarily be employed as a covering for buildings, gables, dormers and architectural structures in general.

This being the object of my invention its essential features reside in the tile now to be particularly described, reference being had to the accompanying drawing, in which—

The numeral 1, represents a highly ornamental projecting or raised shield-shaped boss or tile, said boss being embellished by a geometric anthemion ornament as shown, which is formed by alternating sunken and raised arises 2 and 3 respectively, converging to a common center, as also the center of the shield, and there terminating in a small pear-shaped boss 4.

Having thus described my invention, what I claim, and desire to secure by Letters Patent, is—

The design for an ornamental tile for roofing, substantially as herein shown and described.

In testimony whereof I subscribe my signature in presence of two witnesses.

WM. H. MULLINS.
